INSULATED BOAT CONSTRUCTION

Filed Aug. 22, 1931

UNITED STATES PATENT OFFICE

1,991,675

INSULATED BOAT CONSTRUCTION

Carl Hussman, Chicago, Ill., assignor to United States Gypsum Company, Chicago, Ill., a corporation of Illinois

Application August 22, 1931, Serial No. 558,684

5 Claims. (Cl. 114—78)

This invention relates to boat constructions, and has reference more particularly to boat constructions in which the engine room is provided with sound and heat insulating bulkheads for preventing sound and heat from passing into the boat cabins through the bulkhead.

Motor boats, yachts, steamships, and other types of power-driven water craft are usually provided with an engine room which is often located amidships where the noise and heat from the engines, air compressor and other auxiliary machinery is apt to disturb the occupants of adjoining cabins. It is desirable, therefore, that sound-proof bulkheads be built into the walls of the engine room to isolate the sound and prevent the annoyance of the passengers and crew of the boat.

An object of this invention, therefore, is to provide a sound-proof bulkhead for use in boats which will isolate the sound and heat of the engine room and prevent the annoyance of people on the boat; also to improve boat constructions in other respects hereinafter specified and claimed.

Reference is to be had to the accompanying drawing forming a part of this specification, in which

Fig. 1 is a diagrammatic sectional elevation of my improved bulkhead construction for boats, Fig. 2 is an elevation of the bulkhead with parts broken away to disclose the construction,

Fig. 3 is a transverse, sectional view through the bulkhead taken on line 3—3 of Fig. 1,

Fig. 4 is a sectional elevation on a large scale through the bulkhead, and

Fig. 5 is a sectional plan view on a large scale showing the method of joining the sound impinging panels.

A power boat 10 is commonly provided with an engine, oil motor 11, or the like, for operating the propeller shaft 12 and causing the propulsion of the boat through the water. The boat is also commonly provided with cabins or decks 13 which adjoin the engine room 14.

In order to separate the engine room 14 from the cabins 13, I provide a sound and heat insulating bulkhead which preferably consists of an outside fiber board facing 15, which may be finished with a plastic paint 16, the joints between adjacent fiber boards being covered with a metal foil 17 to prevent cracking of the plastic paint due to the vibration of the boat and due to strains produced by shrinking and warping of the boards 15. These fiber boards 15 are preferably made of ground wood fiber formed into flat boards and

may be of a thickness of about $\frac{1}{2}$ ". These boards may therefore be termed "synthetic" fiber boards as distinguished from wood which has a lower heat insulating value. Nailing strips 18 are provided adjacent the inside edges of the boards 15, and said nailing strips may be secured by bolts 19 to the leg of a frame angle 20. The angle 20 is connected at its ends to the main frame structure of the boat.

The bulkhead proper may consist of an eighth inch steel plate 21, or other suitable thickness or material, which may be secured to an angle leg 22 by welding or otherwise. A light weight panel of synthetic fiber board 23 is preferably provided inside of the engine room 14, said panel having sheets of thin steel 24, or other suitable metal, on each of its faces, preferably attached to the fiber board by a suitable adhesive. The panel 23 is resiliently attached to the bulkhead 21 by means of spring clips having central saddle members 25, integral outstanding loops 26, and clip ends 27 in a plane different from that of the saddle member 25. The two clip ends 27 are preferably connected together by means of a strip of metal 28 to which the clip ends may be spot welded, and the strip 28 is secured to the inner face of the bulkhead 21 by welds 29. A short piece of square tubing 30 or other spacer block, is interposed between the saddle member 25 and the inner sheet 31 of the panel 23. This tube 30 is preferably welded to the saddle member 25, and a bolt 32 passes through said saddle member, tube, sheet 31, panel 23 and sheet 24, to receive a nut 33 for rigidly securing the panel member 23 and its associated metal sheets to the tube 30.

The spring clips permit the light weight panel member 23 to vibrate under the impact of sound waves impinging upon the metal sheet 24 and thus prevent the transmission of sound through the bulkhead 21. The two heat insulating panels 23 and 15 prevent the transfer of heat through the bulkhead construction and thus confine the heat to the engine room to be disposed of by suitable ventilation. Where the edges of the panel 23 adjoin, (Fig. 5) the inside metal sheet 31 is bent at right angles to form an edge covering section 34, which in turn is bent outwardly at an acute angle to form opposed dovetail flanges 35. A sealing strip 36 is provided over the dovetail flanges 35, and said sealing strip is provided with inwardly turned dovetail flanges 37 to cooperate with the flanges 35. After assembly, these flanges 35 and 37 are hammered flat and welds 38 are provided to firmly attach the sealing strip and flanges 37 to the inside metal sheet 35.

24. By this construction, the edges of the fiber panels 23 are protected against moisture infiltration, and the adjoining panels are securely connected together to form a tight but yielding 5 base panel.

By the use of the combined heat and sound insulating construction, I am able to secure a highly effective bulkhead which greatly enhances the comfort of the passengers and crew due to 10 the isolation of heat and sound to the engine room.

Good results can be obtained by eliminating the panel 15.

I would state in conclusion while the illustrated 15 examples constitute practical embodiments of my invention, I do not wish to limit myself precisely to these details, since manifestly, the same may be considerably varied without departing from the spirit of the invention as defined in the appended claims.

Having thus described my invention, I claim as new and desire to secure by Letters Patent:—

1. In a bulkhead construction for boats, a sheet metal panel, a fibrous, low density, synthetic, heat insulating panel in spaced, parallel 25 relation to said metal panel, and resilient spring clips yieldingly connecting said panels so as to retard the passage of heat and sound through said bulkhead.

30 2. In a partition structure, a plurality of fiber

board panels arranged in a plane in substantial edge abutting relation, metal sheets enclosing said panels, flanges extending outwardly from said sheets, and a sealing strip secured to said flanges across the joint between adjacent panels. 5

3. In a boat partition structure, a pair of low density, synthetic, fiber board panels in spaced, parallel relation, facing metal on the exposed faces of said fiber boards, and resilient spring 10 clips yieldingly connecting said panels so as to retard the passage of heat and sound through said bulkhead.

4. In a boat partition structure, a metal panel, a plurality of flat spring clips having outstanding ends secured to said panel, said clips having saddle members, spacers secured to said saddle members, bolts extending outwardly from said spacers, and a heat insulating panel having metal 15 faces and secured by said bolts to said spacers and saddle member.

5. In a partition structure, a plurality of fiber board panels arranged in a plane in substantial edge abutting relation, metal sheets on the faces of said panels, flanges extending outwardly from said sheets, a sealing strip secured to said flanges across the joint between adjacent 20 panels, and a plurality of spring members resiliently supporting said panels. 25
